UNITED STATES PATENT OFFICE.

THOMAS A. MANLEY, OF AUBURN, NEW YORK, ASSIGNOR TO OHIO TOOL COMPANY, OF AUBURN, NEW YORK, A CORPORATION OF NEW YORK.

PLANE.

1,021,369.

Specification of Letters Patent.

Patented Mar. 26, 1912.

Application filed January 18, 1912. Serial No. 671,879.

To all whom it may concern:

Be it known that I, THOMAS A. MANLEY, a citizen of the United States, residing at Auburn, in the county of Cayuga and State 5 of New York, have invented certain new and useful Improvements in Planes, of which the following is a specification.

This invention relates to improvements in planes, and has for its object to provide 10 novel, simple, convenient and effective means for adjusting the plane-frog longitudinally for facilitating the setting of the bit or plane iron in different positions in the throat of the plane body.

15 A further object is to provide novel and simple means for locking the frog after the same has been adjusted. And a particular object of the invention is to provide convenient and effective means for adjusting and 20 locking the frog without disturbing the plane iron and related parts.

The various features and parts and the operation of the same, will be fully set forth in the detailed description which follows, 25 illustrated in the accompanying drawing, and then particularly pointed out in the claims.

Figure 1 is a side elevation and part section of my complete plane. Fig. 2 is a horizontal section, taken on line 2—2 of Fig. 1. 30 Fig. 3 is a vertical cross-section, taken on line 3—3 of Fig. 2. Fig. 4 is a horizontal section similar to Fig. 2; showing a modification of the locking and adjusting means. Fig. 5 is a vertical cross-section, taken on 35 line 5—5 of Fig. 4.

Similar characters of reference designate like parts throughout the several views.

In the drawing, 2 represents the body of 40 the plane, 3 the sole, 4 the throat or mouth, and 5 the cheeks or lateral guards which are formed integral with the body. The rear side or edge of the throat 4 is formed sharp and thin, and then the metal inclines 45 upwardly and rearwardly at a slight angle for forming a smooth bearing surface 6 which extends across the upper side of the sole 3, to receive a correspondingly formed forwardly projecting portion 7 of the frog.

50 8. The frog 8 consists of an irregularly shaped casting or part having a rearwardly and upwardly inclining top surface 9, for receiving and supporting the plane iron or bit 10, and having a substantially plain horizontal bottom 11, which bears and slides

upon a comparatively long elevated step or portion 12, preferably an integral part of the body of the plane. The elevation or seat 12 is disposed a short distance rearwardly of the inclined bearing 6, and its top 60 surface lies in a higher plane than the said bearing. The under side of the frog is correspondingly shaped, so that when the bottom 11 of the frog rests upon the elevation 12, the forward end 7 approaches close 65 to the sloping surface 6.

13 represents like inwardly facing angular ribs or tongues formed horizontally on the cheek pieces 5, directly above the opposite side-edges of the elevated bearing 12, 70 and 14 represents hollow corners or grooves formed in the opposite bottom corners of the frog, the said hollow corners preferably being formed right-angled, so as to clear the ribs 13 when the frog is moved to and 75 fro over the body of the plane. The tongues or ribs 13 are triangular in cross-section, and preferably extend the length of the elevated bearing 12, and they are disposed parallel to said bearing, so that the frog, when 80 operatively connected with the tongues, may be freely moved forward and backward in a true and level plane. The tongues 13 are of sufficient length and strength to effectually hold the frog from chattering while the 85 plane is in operation.

To hold the frog 8 in place on the base 2, and yet allow said part to be freely moved to and fro for adjusting the cutting-blade or bit 10 relatively to the throat 4, the underside of the frog is provided with a broad transverse dove-tail groove or slot 15, in which is operatively fitted a pair of correspondingly shaped keys or locking members 16—17. The keys 16—17 are disposed 90 end to end, in the slot or way 15, and their combined length is slightly less than the breadth of the bearing surface 12 beneath the tongues or guides 13, the outer ends of the keys 16—17 then project beyond each 100 side of the bottom of the frog, as shown in Figs. 2 and 3. The outer ends of the keys 16—17 are beveled to correspond to the under-cut sides of the tongues 13 (see Fig. 3). The abutting ends of the keys 16—17 105 are provided with transverse concaves 18, the said concaves tapering toward the forward end of the frog.

19 represents a set-screw having a tapering point 19' extending beyond the threads, 110

the said point being tapered to correspond to the concaves 18 of the keys. The set-screw 19 passes through a threaded hole 20 formed in the rear portion of the frog (see 5 Figs. 1 and 2), the hole 20 being arranged to bring the set or locking screw 19 into coincidence with the abutting ends of the keys 16—17. When the keys 16—17 are brought together, the opposite concaves 18 10 form a tapering hole corresponding to the tapering point 19' of the set-screw. In practice, the length of the tapering end of the screw 19 is such that its point 19' normally projects part way into the tapering 15 hole 18 between the ends of the keys. To lock the frog in any adjusted position the wedge screw 19 is driven inwardly until its tapering end 19' spreads and forces the keys 16—17 in opposite directions against 20 the beveled under-sides of the tongues or ribs 13 (see Fig. 3). Any desired pressure or tension may be produced by means of the wedging of the screw 19 between the abutting ends of the keys 16—17. The said 25 keys are preferably broad enough to insure a firm bearing beneath and against the tongues 13, and will hold the frog rigidly in place. By the provision of the beveled ends of the keys 16—17, when the screw 19 30 is driven inwardly for spreading said keys, they exert a downward pressure which forces and holds the frog rigidly against the bearing surfaces of the elevated seat 12. When the keys are made as shown in Figs. 35 1, 2 and 3, they are not liable to wear seats in the under-side of the ribs 13, which will interfere with the fine and accurate adjustment of the frog. In practice the key 16 is made longer than the key 17, so as to 40 bring the abutting ends (18) to one side of the longitudinal center of the body 2. Under this arrangement the screw 19 may be readily manipulated without interference by the handle 21 or the bit adjusting- 45 screw 22.

To assemble the frog and plane body, the frog is inserted between the cheeks 5 just forwardly of the tongues 13, and when brought to the proper position the projecting beveled outer-ends of the keys 16—17 50 may be entered underneath the tongues 13, after which the frog may be moved rearwardly until brought to the desired position. In constructing the plane body and the frog, the tongues 13 and the hollow-corners 14 are arranged so that the bottom 55 11 of the frog will rest firmly upon the upper surface of the elevated seat 12.

To adjust the frog to and fro longitudinally, I provide an adjusting screw 25 which enters a threaded hole 26 in the rear side of the frog 8 above the bottom 11. The screw 25 is preferably positioned at one 60 side of the longitudinal center of the plane, so as to facilitate adjusting the frog without

interference by the handle 21 or other parts of the plane. The screw 25 is held from longitudinal movement by means of a yoke 27 which forms the upright arm of an L-shaped bracket 28 which is mounted upon the upper side or face of the sole 3, by means of a screw or pin 29. The screw 25 has a circumferential groove 25' to receive the yoke 27. When the screw 25 is turned in either direction by hand or by means of a screw-driver, it will move the frog to and fro longitudinally on the base 2. The provision of the guide tongues 13 and the corresponding beveled keys 16—17 will prevent vertical movement of the frog, as well as, 70 lateral and longitudinal rocking of said part relative to the base, and this arrangement also insures the smooth, free and true horizontal movement of the frog on the elevated bearing surface 12. The provision and arrangement of the tongues 13 and the locking keys or members 16—17 will also effectually obviate the chattering of the bit when the plane is operated over hard or 75 burly wood.

Figs. 4 and 5 illustrate a modification of the adjusting and locking parts, and also a slight modification of the form and arrangement of the bottom of the frog 8'. The lower side corners of the frog 8' are provided with annular grooves 14', which conform to the shape of the tongues 13' (see Fig. 5). The locking means comprise a pair of like round keys or pins 30 and 31 which are loosely disposed in a hole 32 which 80 passes transversely through the lower portion of the frog. The outer ends of the pins or keys 30 and 31 are beveled to correspond to the under-cut sides of the guide ribs 13', and their combined length is slightly less than the distance between the ribs 18', for permitting endwise adjustment, the same as the keys 16—17. The keys 30 and 31 are preferably the same length, and their inner ends meet at the transverse center of the frog. The abutting ends 33 of the keys 30—31 are formed concave, and taper forwardly, similar to the construction shown and described for the keys 16—17. To lock the frog 8' from longitudinal movement, I 85 provide a screw 34 which enters a threaded hole 35 formed centrally in the rear-part of the frog 8'. The inner end of the screw 34 is provided with a tapering point 36, which is arranged to enter the tapering concaves arranged in the abutting ends of the keys 30 and 31 for wedging them apart. When the screw 34 is driven inwardly the point 36 spreads the keys 30—31 and forces 90 said keys laterally for tightly engaging the underside of the ribs 13'. When the screw 34 is driven tightly between the keys, the frog 8' will be held from longitudinal movement. The arrangement of the dove-tail tongues 13' and the similar grooves 14' is 95 100 105 110 115 120 125 130

such that, the frog cannot be moved vertically until it is withdrawn free from the ribs. To adjust the frog 8' to different positions longitudinally, the screw 34 is first 5 loosened up, and then the frog may be shifted to and fro, and set in the desired position, by hand.

The plane iron or bit 10 is provided with the usual guard plate 37, and is held in 10 place by a cap 38, which is fitted with the usual clamping part 39.

40 represents a screw carried by the frog for engaging the cap 38. The adjusting screw 22 is employed for shifting the plane 15 iron longitudinally on the frog, and a lever 41 is employed for adjusting the plane iron laterally.

The locking means comprising the keys and the wedge screws are extremely simple, 20 yet affording powerful means for locking the frog to the frame. When these parts are properly made and assembled, but a slight movement of the screws 19 and 34 in either direction will effect the rigid locking 25 or the unlocking and freeing of the frog. The broad keys 16—17 coöoperating with the side ribs 13 tend to steady the frog during its forward and backward movements. The disposition of the screws 19 and 25 at or 30 near the sides of the plane render the locking and adjusting parts conveniently accessible, and in view of the location and arrangement of these parts the locking and adjusting of the frog may be accomplished 35 without disturbing the plane-iron or any other part.

Having thus described my invention what I claim as new and desire to secure by Letters Patent, is—

40 1. In a plane, the combination with a sole having a throat and an elevated seat arranged rearwardly of said throat, of a frog having a plane bottom adapted to rest and slide upon said seat, said frog having longitudinal 45 grooves formed in its opposite bottom corners, a pair of angular tongues carried by the body of the plane, said tongues received by said grooves, and adjustable means carried by said frog adapted to engage 50 said tongues for guiding and locking said frog.

2. In a plane, the combination with a sole having a throat and an elevated seat arranged rearwardly of said throat, of a frog 55 having a plane bottom adapted to rest and slide upon said seat, said frog having longitudinal grooves formed in its opposite bottom corners, a pair of angular tongues carried by the body of the plane, said tongues received by said grooves, adjustable means 60 carried by said frog adapted to engage said tongues for guiding said frog, and a screw coöoperating with said means for locking said frog rigidly to the elevated seat.

65 3. In a plane, the combination with a sole

having a throat and an elevated seat arranged rearwardly of said throat, of a frog having a plane bottom adapted to rest and slide upon said seat, said frog having longitudinal grooves formed in its opposite bottom 70 corners, a pair of angular tongues carried by the body of the plane, said tongues received by said grooves, adjustable means carried by said frog adapted to engage said tongues for guiding and locking said frog, and a swivel-screw for adjusting said frog to different positions on said sole.

4. In a plane, the combination with a sole having spaced cheek pieces and having an elevated seat between said cheek pieces, of horizontal guide-ribs formed on the inner sides of said cheek pieces above and parallel to the said seat, a frog having a plane bottom 80 slideable upon said seat, the opposite lower corners of said frog cut away to clear 85 said ribs, a pair of keys disposed end to end in a transverse slot formed in the bottom of said frog, said keys having their outer ends beveled to pass under and to engage said ribs, and a tapering screw for spreading said 90 keys apart for locking the frog to said ribs.

5. In a plane, the combination of a sole having a transverse throat and an inclined bearing adjacent the throat, and having an elevated seat adjacent the inclined bearing, 95 triangular ribs formed above and parallel to the said elevated seat, a frog having a plane bottom surface adapted to engage and slide upon said elevated seat between said ribs, said frog having portions cut-away for 100 clearing said ribs, and a pair of transversely movable keys carried by said frog adapted to engage said ribs for guiding and also for locking said frog.

6. In a plane, the combination of a frame 105 comprising a sole and spaced cheek pieces, a raised seat formed on the sole between the cheek pieces, an inwardly facing tongue carried by each cheek piece disposed horizontally above said raised seat, said tongues 110 having their facing sides under-cut, a frog slideable on the said raised seat between the said tongues, but free from said tongues, transversely movable keys carried by the frog having beveled outer ends adapted to 115 slide beneath the under-cut sides of said tongues for guiding said frog when moved to and fro on said seat, and a wedge-screw carried by said frog adapted to force and hold said keys against said tongues for locking said frog from movement in any direction.

7. In a plane, the combination with a body having an integral elevated seat lying between like cheeks projecting upwardly on its opposite sides, and ribs formed on the inner sides of said cheeks and overhanging said elevated seat, said ribs disposed parallel to the said elevated seat and also to the sole 125 of the body, of a frog having a plane bot- 130

tom surface adapted to engage and slide upon the said elevated seat, said frog having its opposite bottom corners cut-away to receive said ribs, and means carried by said frog adapted to engage said ribs for holding said frog from vertical movement.

8. In a plane, the combination of a frame comprising a sole and spaced cheek pieces, a raised seat formed on the sole between the 10 cheek pieces, an inwardly facing tongue carried by each cheek piece disposed horizontally above said raised seat, said tongues having their facing sides under-cut, a frog 15 slideable on the said raised seat between the said tongues, but free from said tongues, transversely movable keys carried by the frog adapted to slide beneath the under-cut sides of said tongues for guiding said frog when moved to and fro on said seat, a 20 wedge-screw carried by said frog adapted to force and hold said keys against said tongues for locking said frog from movement in any direction, and a swivel-screw for adjusting said frog to different positions in the said 25 frame.

9. In a plane, the combination with a body having an integral elevated seat, said body having like cheeks projecting upwardly on its opposite sides, and ribs formed 30 on the inner sides of said cheeks and overhanging said elevated seat, said ribs disposed parallel to the said elevated seat and also to the sole of the body, of a frog having a plane bottom surface adapted to engage and slide upon the said elevated seat, said frog having its opposite bottom corners cut-away to receive said ribs, means 35 carried by said frog adapted to engage said ribs for guiding said frog during its longitudinal movements, and means for adjust-

ing said frog to different positions on said elevated seat.

10. In a plane, the combination of a body having vertically disposed lateral guards, ribs carried by the inner faces of said guards, said ribs arranged parallel to the sole of said body, an elevated step disposed beneath and parallel to said ribs, a frog having a substantially flat bottom adapted to rest and slide upon said elevated step, the 45 opposite sides of said frog cut-away to clear said ribs, transversely disposed keys carried by said frog; the outer ends of said keys projecting beyond said frog adapted to engage the under-cut edges of said keys for 50 holding said frog firmly upon said step, said keys and said ribs coöperating for guiding said frog when moved to and fro on said body, and a wedge-screw carried by said frog adapted for spreading said keys for 55 rigidly locking said frog to the said ribs.

11. In a plane, the combination of a sole having a transverse throat and an inclined bearing adjacent the throat, and having an elevated seat adjacent the inclined bearing, 60 triangular ribs disposed above and parallel to the said seat, a frog having a plane bottom surface adapted to engage and slide upon said seat between said ribs, a pair of 65 keys carried by said frog adapted to engage said ribs for guiding and also for locking said frog, and a screw for adjusting said frog to different positions relative to said throat.

In testimony whereof I affix my signature 75 in presence of two witnesses.
